SNUBBER

David M. Light, Chicago, Ill., assignor to American Steel Foundries, Chicago, Ill., a corporation of New Jersey

Application October 30, 1942, Serial No. 463,954

20 Claims. (Cl. 267—9)

My invention relates to friction absorbing devices and more particularly to such a device commonly called a snubber which, when associated with a group or nest of springs, serves to dampen the vibrations thereof in such manner as to substantially eliminate harmonic vibrations of said springs.

My novel snubber is particularly designed for application to a coil spring group affording support for the bolster of a railway car truck wherein said snubber may be substituted for one or more of the coil springs constituting said group as desired. It will, however, be understood that my novel snubber or friction absorbing device may be used for any analogous purpose to which it is suited.

A specific object of my invention is to devise a snubber such as above described in which a pair of followers are in frictional engagement with a plurality of associated friction shoes, the shoes being urged into said engagement by means of a novel spring seat casting in wedge engagement with the shoes, said casting affording a seat for an associated spring sleeved over one of said followers and afforded a seat against a flange thereon.

A further object of my invention is to provide an arrangement such as above described in which the follower over which the above-described spring is sleeved is split into a plurality of segments whereby each of said segments may be urged into frictional engagement with said spring by means of the friction shoes above described.

Still another object of my invention is to devise in combination with the above-described snubber a novel means for retaining the device in assembly on the release stroke thereof, said means comprising a member received through aligned passages in the spaced followers and in the spring seat casting and said member having at opposite ends thereof means for abutment with respective followers in order to limit their movement away from each other on the release stroke.

Still another object of my invention is to design a novel spring seat casting comprising a ring-like base having an opening therethrough for the reception of an associated follower and affording about the margin thereof a seat for an associated spring, and said spring seat casting also comprising an integral yoke or bridge spanning said opening and comprising wedge surfaces for engagement with associated friction shoes, said bridge being provided with an opening for the reception of the securing member above described.

In the drawings,

Figure 1 is a side view of my novel snubber, the left half thereof being a view in elevation and the right half thereof being a sectional view taken substantially in a vertical plane bisecting the snubber as indicated by the line 1—1 of Figure 2, and Figure 2 is a top view of the structure shown in Figure 1, the left half thereof being a plan view, and the right half thereof being a sectional view taken in the plane indicated by the line 2—2 of Figure 1.

Figures 3, 4 and 5 show in detail my novel form of spring seat casting, Figure 3 being a side elevation taken from a shoe engaging face thereof, Figure 4 being a plan view taken from the top as seen in Figure 3, and Figure 5 being a sectional view taken substantially in the plane indicated by the line 5—5 of Figure 4.

Describing my invention in detail, a follower 2, here shown as a top follower, is divided or split into a plurality of substantially identical segments or friction members 4, 4. In the modification shown, the follower 2 comprises a pair of segments 4, 4 cooperating with a pair of friction shoes hereinafter more fully described, but it will be readily understood by those skilled in the art that if desired, said follower 2 may be split or divided into three or more segments 4, 4 each cooperating with an associated friction shoe. Each of the segments 4 comprises a base 6 affording a seat as at 8 (Figure 1) for an associated supporting member such as a bolster of a railway car truck, said seat being tapered at 10 to afford a rocking movement of said supported member. Each base 6 on the edge thereof adjacent the base on the other segment 4 is provided with a depression 12 affording convenient means for the reception of positioning means on the associated supported member, and the base 6 is also provided on said edge a recess 14 to afford clearance for an associated securing member in a manner hereinafter more fully described.

Projecting angularly from the base 6 of each segment 4 is a pedestal or friction stem 16 comprising on the inner surface thereof a diagonal V-shaped friction face 18 relieved as at 20 in the customary manner to prevent the wearing of a shoulder thereon, said face being in complementary engagement as at 22 with a friction shoe generally designated 24, and on the opposite side thereof the pedestal 16 is provided with an articulate friction surface 26 in complementary frictional engagement as at 28 with the coil spring 30 sleeved over the pedestals 16, 16 and conveniently formed with a flat surface to accommodate the above-mentioned frictional engagement at 28.

As here shown the spring 30 is formed as an octagonal bar, but it will be readily understood that said spring may be of any desired section. The spring 30 is seated at the upper end thereof as at 32 against flanges 34, 34 on the respective segments 4, 4 of the top follower, and said spring 30 is seated at the bottom thereof as at 36 on the base 38 of my novel spring seat casting generally designated 40 and shown in detail in Figures 3 to 5 inclusive.

My novel spring seat casting may be formed of any suitable material such as iron or steel and may be provided with the before-mentioned base 38, said base being a generally ring-like disc provided with an opening 42 therethrough and serving a purpose hereinafter more fully described. At opposite sides of the opening 42 spaced legs 44, 44 project angularly from the base 38, and integrally formed with the ends of said legs remote from said base is a transverse web 46 presenting on the surface thereof facing the base 38 the oppositely directed diagonal friction surfaces 50, 50 for wedge engagement as at 52, 52 (Figure 1) with the friction shoes 24, 24. The web 46 is formed with an opening 54 therethrough formed and arranged for the reception of an associated securing member serving to retain the snubber in assembly on the release stroke thereof, as hereinafter more fully described. It may be noted that the web 46 may be formed of any convenient section affording the before-mentioned diagonal friction surfaces 50, 50; however, the V-section shown is regarded as preferably in affording a relatively light and suitably strong structure for the purpose. It may be noted from a consideration of Figures 3 to 5 inclusive that the web 46 and the spaced legs 44, 44 connecting said web to the base 38 form a yoke or bridge designated 56 (Figure 3).

A bottom follower generally designated 58 comprises the substantially annular plate-like base 60 affording a seat as at 62 (Figure 1) for the snubber upon an associated supporting member, the base 60 being tapered at 64 to afford a rocking movement for the snubber on the seat 62 and the base 60 comprises the opening 66 therethrough, said opening communicating with the chamber 68 formed within the hollow projection 70 extending upwardly from the base 60; said projection comprising on opposite sides thereof friction faces in complementary diagonal face engagement at 72, 72 with the respective friction shoes 24, 24.

Means is provided for retaining the snubber in assembled relationship on the release stroke thereof, said means comprising a bolt or other suitable member 74 extending through the passages 14 and 54 through the top follower and the web 46 of the spring seat casting respectively, said bolt also extending between the friction shoes 24, 24 and being afforded clearance therefrom by means of recesses therein indicated at 76, 76 (Figure 2), and said bolt also extending through an opening 78 in the projection 70 formed on the base 60 of the bottom follower 58. The bolt is provided with a head 80 adapted to engage the base 6 of each segment 4 of the top follower as at 82 (Figure 1) within the depression or recess 12, and the bolt is afforded a nut 84 or other convenient securing means on the opposite end thereof adapted to engage the projection 70 of the bottom follower 58 as at 86. It will be understood, that if desired, the nut 84 may be secured by any convenient means such as by welding or by peening the end of the bolt.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a friction absorbing device, a top follower divided into a plurality of segments each presenting an inner diagonal V-shaped friction face and an outer arcuate friction surface, a plurality of shoes each engaging one of said faces, a spring seat member comprising a yoke in diagonal face engagement with the tops of said shoes, and a spring seat integrally formed with the bottom of said yoke, an opening through said seat, a coil spring sleeved over said top follower in frictional engagement with the segments thereof and seated at opposite ends thereof against means on said segments and against said seat, a bottom follower extending through said opening in diagonal face engagement with said shoes, and securing means extending through aligned openings in the bottom follower and said yoke and also extending between the segments of said top follower, said securing means having means for abutment with said top and bottom followers to limit expansion of the device.
2. In a friction absorbing device, a top follower divided into a plurality of segments each presenting an inner diagonal V-shaped friction face and an outer arcuate friction surface, a plurality of wedges each engaging one of said faces, a spring seat member comprising a yoke in diagonal face engagement with the tops of said wedges, and a spring seat integrally formed with the bottom of said yoke, an opening through said seat, a coil spring sleeved over said top follower in frictional engagement with the segments thereof and seated at opposite ends thereof against means on said segments and against said seat, and a bottom follower extending through said opening in diagonal face engagement with said wedges.
3. In a friction absorbing device, a follower divided into a plurality of segments each having an inner friction face and an outer friction surface, friction shoes in engagement with respective faces, a yoke in diagonal face engagement with corresponding ends of said shoes, a ring-like base on said yoke affording a spring seat, another follower sleeved within said base and in diagonal face engagement with the opposite ends of said shoes, and a coil spring sleeved over said split follower in frictional engagement with said surfaces and seated at opposite ends thereof against said spring seat and against means on the segments of said split follower.
4. In a friction absorbing device, a follower comprising internal friction surfaces, friction shoes in engagement with respective of said surfaces, a member comprising a yoke in diagonal face engagement with the adjacent ends of said shoes, and a base on said yoke affording a spring seat, an opening through said base, another follower projecting through said opening in diagonal face engagement with the opposite ends of said shoes, and a compression spring abutting said seat and bearing against the first-mentioned follower, said spring being sleeved over said first-mentioned follower.
5. In a friction absorbing device, a follower divided into a plurality of segments each having an internal friction face and external friction surface, friction means in engagement with re-

spective of said faces, a member in wedge engagement with said friction means and affording a spring seat, resilient means sleeved over said divided follower in frictional engagement with said surfaces and in abutment with said seat and with seating means on said segments, and means associated with said friction means for moving the same against said faces and affording a seat for the device.

6. In a friction absorbing device, a follower divided into a plurality of segments, a plurality of friction shoes between said segments and in frictional engagement therewith, wedge means engaged with opposite ends of said shoes to urge said shoes into said engagement, one of said wedge means affording a spring seat and the other of said wedge means affording a seat for the device, and resilient means sleeved over said segments in frictional engagement therewith and seated at opposite ends against said spring seat and said segments.

7. In a friction absorbing device, a follower comprising internal friction surfaces, friction shoes therebetween in engagement with respective of said surfaces, a member comprising a yoke in diagonal face engagement with the adjacent ends of said shoes, and a base on said yoke affording a spring seat, an opening through said base, another follower projecting through said opening in diagonal face engagement with the opposite ends of said shoes, and a spring abutting said seat and under compression between said seat and the first-mentioned follower.

8. In a friction absorbing device, a follower comprising internal friction surfaces, friction shoes engaged therewith, a member in wedge engagement with corresponding ends of said shoes and affording a spring seat, another follower in wedge engagement with the opposite ends of said shoes and affording a seat for the device, and resilient means abutting said spring seat and means on the first-mentioned follower, said resilient means being sleeved over said first-mentioned follower.

9. In a friction absorbing device, a follower having internal friction surfaces, friction shoes engaged therewith, a member in wedge engagement with said shoes and affording a spring seat, resilient means sleeved over said follower and abutting said seat and means on said follower, and a spaced follower in wedge engagement with said shoes and affording a seat for one end of said device, the first-mentioned follower being split into a plurality of segments to afford frictional engagement thereof with said resilient means.

10. In a friction absorbing device, a compression spring, a split follower affording a seat therefor and presenting internal friction surfaces therewithin, friction shoes engaging said surfaces, a yoke member affording a seat for the opposite end of said spring and having wedge means bearing against the ends of said shoes remote from said last-mentioned seat, another follower in wedge engagement with the near ends of said shoes, and securing means extending between said followers.

11. In a friction absorbing device, spaced followers affording seats for opposite ends of said device, one being split into a plurality of segments, friction shoes each in engagement with both followers, a member in wedge engagement with said shoes, and resilient means sleeved over said split follower and seated thereagainst and against said member, said resilient means being in frictional engagement with said segments.

12. In a snubber, a compression spring, a follower seated thereagainst and presenting therewithin opposed friction surfaces, friction shoes engaging said surfaces, a wedge casting affording a seat for the opposite end of said spring and having wedge engagement with the ends of said shoes remote from said last-mentioned seat, another follower in wedge engagement with the opposite ends of said shoes, and securing means extending through said casting and said followers.

13. In a snubber, a compression spring presenting internal friction surfaces, a follower affording a seat for one end of said spring and having arcuate walls extending therewithin for engagement with said surfaces, said walls presenting internal friction faces, friction shoes engaging said faces, a member affording a seat for the opposite end of said spring and having wedge engagement with the ends of said shoes remote from said last-mentioned seat, a follower abutting the opposite ends of said shoes, and retaining means between said followers.

14. In a snubber, a compression spring presenting internal friction surfaces, a follower affording a seat for one end of said spring and having arcuate walls extending therewithin for engagement with said surfaces, said walls presenting internal friction faces, friction shoes engaging said faces, a member affording a seat for the opposite end of said spring and having wedge engagement with the ends of said shoes remote from said last-mentioned seat, a follower in wedge engagement with the opposite ends of said shoes, and retaining means between said followers, the engaging faces between said shoes and said first-mentioned follower being along inclined V-shaped areas.

15. In a snubber, a compression spring, a split follower seated against said spring and presenting friction walls therewithin in engagement therewith, friction shoes engaging said walls, a member affording a seat for the opposite end of said spring and in wedge engagement with the ends of said shoes remote from said last-mentioned seat, another follower in wedge engagement with the near ends of said shoes, and securing means between said followers.

16. In a friction absorbing device, a compression spring, a split follower affording a seat therefor and presenting friction walls therewithin, wedge means in diagonal face engagement with said walls, a member affording a seat for the opposite end of said spring and in wedge engagement with like ends of said wedge means, an opening in said member, a spaced follower projecting through said opening in wedge engagement with the opposite ends of said wedge means, and securing means for said device, closing of said device being operative to urge said wedge means against said walls.

17. In a snubber, a compression spring presenting internal friction areas, a split top follower seated against one end of said spring with walls therewithin, shoes having wedge engagement with said walls, a spring support member abutting the opposite extremity of said spring with wedge means engaging the ends of said shoes remote from said extremity, a bottom follower in wedge engagement with the opposite ends of said shoes, and securing means for said followers.

18. In a snubber, a split top follower having internal friction faces and external friction surfaces, shoes in wedge engagement with respective of said faces, a member in wedge engagement with corresponding ends of said shoes and

affording a spring seat, a bottom follower in wedge engagement with the opposite ends of said shoes, and resilient means sleeved over said split follower and in frictional engagement with the external surfaces thereof and seated at opposite ends against said seat and said top follower.

19. In a snubber, a compression spring presenting internal friction areas, a split top follower seated against one end of said spring with walls therewithin, shoes having wedge engagement with said walls, a spring support member abutting the opposite extremity of said spring with wedge means engaging the ends of said shoes remote from said extremity, a follower in wedge engagement with the opposite ends of said shoes, and securing means for said followers, reciprocal movement between said followers being operative to wedge said shoes against said walls and urge

the same into frictional engagement with said spring, said walls having inner surfaces diverging toward said bottom follower.

20. In a snubber, a compression spring presenting internal friction areas, a split top follower seated against one end of said spring with walls therewithin, shoes having wedge engagement with said walls, a spring support member abutting the opposite extremity of said spring with wedge means engaging the ends of said shoes remote from said extremity, a bottom follower in wedge engagement with the opposite ends of said shoes, and securing means for said followers, said shoes engaging said top follower walls along V-shaped tapering friction surfaces and relieved areas above said surfaces to accommodate wear therealong.

DAVID M. LIGHT.
